UNITED STATES PATENT OFFICE.

ERNEST E. HOWARD AND LOUIS R. ASH, OF KANSAS CITY, MISSOURI.

SUBSTRUCTURE CONSTRUCTION.

Application filed September 12, 1921. Serial No. 499,945.

To all whom it may concern:

Be it known that we, ERNEST E. HOWARD and LOUIS R. ASH, citizens of the United States, residing at Kansas City, in the county of Jackson and State of Missouri, have invented certain new and useful Improvements in Substructure Construction; and we do declare the following to be a full, clear, and exact description of the invention, 10 such as will enable others skilled in the art to which it appertains to make and use the same, reference being had to the accompanying drawings, and to the figures of reference marked thereon, which form a part of this 15 specification.

Our invention relates to a method of construction for bridge foundations and particularly contemplates the rigid anchorage of the supporting structure by penetrating 20 the bed rock as distinguished from a relatively very shallow excavation into rock, or its mere support thereon.

Heretofore it has generally been the practice to sink the supporting structure only 25 to or slightly into bedrock to secure anchorage against sliding but without securing rigid lateral support except that provided by the softer material overlying bedrock. Often where this softer material was shallow or subject to scour it has necessitated an 30 expensive type of foundation to insure lateral strength. Our invention relates to a method of construction which provides anchorage into the bedrock without the necessity for an expensive caisson or a massive 35 foundation which otherwise would be necessary.

In practising our improved method, the 40 rock is drilled into preferably with a rotary drilling rig, such as is commonly used for oil wells to receive a tube such as oil well casing, the casing being sunk into the hole thus drilled and extending up to a point above the water level. The casing is then 45 filled with reinforced concrete, thus securing a solid column of reinforced concrete with a metallic sheathing, extending deep enough into the rock to afford lateral as well as vertical support and constituting 50 what is termed in engineering practice, a fixed end column. The upper parts may be built upon the columns thus provided, the reinforcing of the columns extending into the shafts or coping of the upper parts to 55 tie the parts together and provide a pier.

The number of tubes and nature of the

upper parts connecting them may vary according to size and type of bridge, and, while we describe the invention in its relation to bridges, it should be understood that the method may be employed for other structures, such as wharfs, docks, etc.

The invention contemplates certain refinements of this generic idea which will be specifically described hereinafter, reference being had to the accompanying drawings, in which,

Fig. 1 is a side elevational view of a bridge constructed in accordance with our invention, illustrating a six-column pier with shaft.

Fig. 2 is a vertical sectional view of a bridge, illustrating a four-column pier with web and coping.

Fig. 3 is a cross section on the line 3—3, Fig. 2, and

Fig. 4 is an enlarged vertical, longitudinal section on the line 4—4, Fig. 2.

Referring to the drawings by numerals of reference:

1 designates the stream, 2 the soil and sands of the bed, and 3 the bed rock. In carrying out our invention we drill anchoring holes or recesses 4 into the bed rock to a suitable depth for forming a firm anchorage for the columns, and into the holes thus formed we sink the column sheathing, preferably consisting of oil well casing 5. The sheathing is continued above the surface of the stream to a height dependent upon the type of bridge and the height at which the superstructure is to be supported above the water level. If the support is to be continued upwardly as a shaft, the sheathing may terminate at such a point above the water level as to avoid intake of water. In other types, the sheathing may extend to a height to directly support slabs, coping or girders.

After the sheathing is set, reinforced concrete is introduced thereinto to form a solid concrete column core 6, reinforced by longitudinal rods 7, which extend above the upper end of the tubing into the shafts 8 (Fig. 1), slabs, or copings as indicated by 9, Figs. 2 and 4. The shafts 8 may support slabs, or copings 9 and rest upon clusters of columns.

With the shaft type of pier (Fig. 1), the sheathing is boxed, preferably to a point below the water line, and the shaft poured to form an integral supporting structure

of the columns, and shaft proper, reinforcing in the sheathing extending into the shaft proper to tie the parts together.

When the sheathing above forms the supporting structure, its reinforcing is bent laterally to be embedded in the web or copings, and the paired sheathings preferably connected by webbing 10.

The method of constructing the bridge as above described particularly commends itself because the foundation or supporting structure can be constructed by an ordinary oil well rig and by employing commercial oil well casing, which is readily available.

We are aware that metallic piles have been used and that reinforced concrete piles and columns are not new, but we are not aware that prior to our invention, bridge supporting structures have been provided by drilling into bed rock and sinking tubes, such as commercial oil well casing, into the holes to constitute columns with fixed lower ends, this being one of the vital features of our invention.

Attention is called to the fact that columns built in accordance with our invention can

be constructed very quickly and will provide an efficient, inexpensive supporting means for the superstructure and that they can be made of any diameters but preferably of relatively small diameters and arranged in clusters.

If the casing becomes rusted or deteriorates, the integrity of the pier will not be destroyed because the concrete core will still constitute an efficient column or support for the superstructure.

What we claim and desire to secure by Letters Patent is:

A bridge structure comprising a set of spaced concrete columns at each side of a bridge structure, a concrete shaft formed integral with the upper ends of each set of columns, concrete webs integral with and connecting the shafts at opposite sides of the bridge structure, and a superstructure carried by the shafts and webs.

In testimony whereof we affix our signatures.

ERNEST E. HOWARD.
LOUIS R. ASH.
